Paul A. Bancel

BY

Robert G. Ogden
his ATTORNEY

UNITED STATES PATENT OFFICE.

PAUL A. BANCEL, OF NUTLEY, NEW JERSEY, ASSIGNOR TO INGERSOLL-BAND COMPANY, OF JERSEY CITY, NEW JERSEY, A CORPORATION OF NEW JERSEY.

EXPANSION JOINT FOR CONDENSERS.

Application filed December 18, 1920. Serial No. 430,414.

To all whom it may concern:

Be it known that I, PAUL A. BANCEL, a citizen of the United States, residing at Nutley, county of Essex, State of New Jersey, have invented certain new and useful Improvements in Expansion Joints for Condensers, of which the following is a specification.

This invention relates to condensers, but more particularly to an expansion joint or member especially suitable for low level jet condensers.

The objects of the invention are to enable an expansion member to be located between the condenser and the removal pump instead of for instance between the turbine and the condenser, secure a greater static head for the removal pump, permit the pump casing to be removed without disturbing the condenser, and cheapen and simplify condenser construction of this type.

Further objects of the invention will hereinafter appear and to all of these ends the invention consists of the apparatus shown in the accompanying drawing, which is a side elevation partly in vertical section, showing a condenser unit and expansion member in accordance with my invention.

Referring to the drawings, A represents a condenser, in this instance indicated as a low level jet condenser, suitably supported beneath the floor line indicated at B, by suitable supports, in this instance shown as I beams C on which the lugs or projections D of the condenser are supported on springs D' so that expansion of the parts including the connection between the condenser and a turbine, for instance, does not produce great strains. The condenser is provided with the usual water chamber E, the inlet F and hand holes provided with the covers G. The usual turbine or other prime mover would be supported in a suitable manner above the condenser A.

A removal pump H is shown supported on the foundation J below the condenser A and in this instance the removal pump comprises the usual lower casing K and the upper casing L provided with the bearing O for the shaft P and having the discharge pipe Q.

The support for the removal pump H is separate and independent from the supports C for the condenser and in accordance with this invention, the condenser and removal pump are connected by an expansion joint.

This expansion joint is preferably shown in the form of a corrugated expansion member R which may be of copper or other suitable material. The bottom of the condenser is provided with the flange S, and the top of the removal pump is provided with the flange T. The flanged edges U and V of the corrugated expansion member R are held against the condenser flange S and the pump flange T respectively by means of the clamping rings W and X and bolts Y. In accordance with this construction, the pump casing can be removed without disturbing the condenser, by loosening the bolts Y and removing the expansion joint. This is a feature of great practical advantage, because otherwise, the entire condenser must be lifted in order to permit the removal of the pump casing. My construction also permits the use of the lower pump casing K of a standard pump instead of requiring a casing of special pump design.

The expansion joint between the condenser and pump provides a greater static inlet head for the removal pump, because otherwise the condenser would be bolted directly to the removal pump. I have found that a gain in head of from 10" to 2' at least may be obtained in this way.

The provision of an expansion joint in the position indicated between the condenser and the pump is cheaper than the construction of an expansion joint between the turbine and the condenser, because the expansion member becomes so much smaller in diameter when located in accordance with this invention.

I claim:

1. The combination of a condenser, resilient supports upon which said condenser rests, a removal pump separately and rigidly supported beneath the condenser, and an expansion joint in the form of a corrugated cylindrical expansion member connecting said condenser and removal pump.

2. The combination of a condenser, resilient supports upon which said condenser rests, a removal pump separately and rigidly supported beneath the condenser, and an expansion joint in the form of a corrugated cylindrical expansion member removably connected between the bottom of said condenser and the top of said removal pump.

3. The combination of a condenser adapt-

ed to be rigidly secured to the under side of a turbine, springs upon which the condenser rests, for yieldingly supporting the weight of the condenser so that expansion 5 of the parts does not produce great strains, a removal pump rigidly mounted on a separate support below the condenser, and a flexible expansion member connecting the condenser to the removal pump.

10 4. The combination of a condenser adapted to be rigidly secured to the under side of a turbine, a removal pump separately and rigidly supported beneath the condenser, an expansion joint in the form of a corrugated 15 cylindrical expansion member removably connected between the bottom of said condenser and the top of said removal pump, and intermediate means located below the position of the turbine but above said expansion joint forming a supporting means for the condenser, said 20 condenser supporting means being separate and independent from the support for the removal pump.

for the condenser, said condenser supporting means being separate and independent from the support for the removal pump.

5. The combination of a condenser adapted to be rigidly secured to the under side 25 of a turbine, a removal pump separately and rigidly supported beneath the condenser, an expansion joint in the form of a flexible expansion member removably connected between the bottom of said condenser and the 30 top of said removal pump, and intermediate means located below the position of the turbine but above said expansion joint forming a supporting means for the condenser, said condenser supporting means being separate 35 and independent from the support for the removal pump.

In testimony whereof I have signed this specification.

PAUL A. BANCEL.
